UNITED STATES PATENT OFFICE.

VINCENT GEHRLEIN, OF ERIE, PENNSYLVANIA, ASSIGNOR TO LOVELL MANUFACTURING COMPANY, OF ERIE, PENNSYLVANIA, A CORPORATION OF PENNSYLVANIA.

WRINGER.

Application filed September 29, 1927. Serial No. 222,825.

This invention is directed to the improvement of the top bar construction of clothes wringers, particularly clothes wringers having metal frames. Features and details of 5 the invention will appear from the specification and claims.

A preferred exemplification of the invention is illustrated in the accompanying drawings as follows:—

10 Fig. 1 shows a front elevation of a wringer partly in section.

Fig. 2 a section on the line 2—2 in Fig. 1.

Fig. 3 a section on the line 3—3 in Fig. 1.

15 Fig. 4 a sectional view showing one end of the top bar and its connection with the stile.

Fig. 5 a top view of the end and stile.

Fig. 6 a section on the line 6—6 in Fig. 1.

20 Fig. 7 a top view of the one end of the wringer.

25 Fig. 1 marks the base of the wringer, 2 the side stiles. The side stiles are formed of channel having the outer face 3 and sides 4. Wringer rolls 5 are of ordinary construction, the lower roll being carried by bearings 6 arranged in the side stile and movable bearings 7 operating against the upper roll and likewise being slidingly mounted in the side stiles. A spring 8 rests on the bearings 7 and a tension screw 9 operates on the central spring. The

30 screw extends through a nut 10 and is provided with an operating handle 11. The nut is swivelled in a fitting 12 fixed in the top bar, this fitting having an opening receiving the nut and provided with projections 13 forming a double keyhole slot. The nut has

35 projections 14 which are adapted to pass through the slots 13 so as to release the nut from the engagement of the fitting. A handle 15 is fixed on the upper end of the nut.

40 By turning the handle 15 the nut is released and consequently a safety release is provided for the wringer. This operates in a manner similar to the release device described in the Misner Reissue Patent, No. 15,865, June 24th, 1924.

45 A top bar 16 is of channel shape having a top plate 17 and side flanges 18. The ends 19 are closed in continuation of the flange, the whole top bar being formed in a single integral stamping. In order to permit of the drawing of the metal to easily make the end closures the side flanges are cut away at 20 equal to the width of the side stiles. Thus the housing effect of the top bar is maintained

between the stiles and the drawing between 55 the ends is readily accomplished.

A lip 21 is struck out of the end forming a shoulder 21^a at the bottom of the struck-out portion and a similar lip 22 is struck out of the outer face of the side stile forming 60 a shoulder 22^a. These shoulders interlock and hold the top bar in place on the side stile against the tension put upon the wringer. In assembling, the opposite end of the top bar is raised, the shoulders put into 65 engagement and the top bar dropped down into its final position, the top bar housing the open ends of the stiles.

At the free, or opposite, end of the top bar I provide a quick detaching means so that 70 the top bar may be readily assembled, or serviced. To accomplish this I provide the two ears 23 which are struck out of the side flanges 4 of the stiles, these forming shoulders which are engaged by the latches 24, the 75 latches being arranged at opposite sides of the wringer and pivoted on a top bar by means of screws 25. The latches at opposite sides are connected by a bail 26 which extends around the end of the wringer so that they are 80 both swung together. An extension 27 on the latch forms a lever by means of which it may be readily swung out of engagement, the extension having a finger piece 28 extending 85 outwardly from the frame.

I am aware that top bars of wringers have been made secured at one side and having means of engagement at the opposite end. Such devices in some instances provide a 90 safety release device but this structure has a servicing feature particularly in connection with a relief device mounted directly on the bar.

What I claim as new is:—

1. In a wringer, the combination of a side stile of channel form having a lip struck out of the outer face of the channel forming a shoulder; a top bar of channel form having a closed end, the end having a notch struck out forming a shoulder interlocking with the shoulder on the bar; and means securing the opposite end of the bar to a stile, said means permitting the engagement of the shoulders and the swinging of the free end of the bar into securing position. 100

2. In a wringer, the combination of a side stile of channel form having a lip struck out of the outer face of the channel forming a 105

- shoulder; a top bar of channel form having a closed end, the end having a notch struck out forming a shoulder interlocking with the shoulder on the bar; and means securing the opposite end of the bar to a stile, said means permitting the engagement of the shoulders and the swinging of the free end of the bar into securing position, said means comprising a latch.
- 10 3. In a wringer, the combination of side stiles; rolls mounted in the side stiles; a tension device operating on the rolls; a top bar of channel form arranged over the stiles, said stiles and top bar having interlocking shoulders at one end and a quick detachable means securing the opposite end of the bar; and a safety release device releasing the tension device, said release device having means operative upon an initial operation to subsequently release the tension on the rolls mounted in the top bar.

In testimony whereof I have hereunto set my hand.

VINCENT GEHRLEIN.

DISCLAIMER

1,709,125.—*Vincent Gehrlein, Erie, Pa. WRINGER. Patent dated April 16, 1929.*
Disclaimer filed June 17, 1940, by the assignee, *Lovell Manufacturing Company.*

Hereby enters this disclaimer to claims 1 and 2 of said patent.
